UNITED STATES PATENT OFFICE.

ALBERT D. RAY, OF CLEVELAND, OHIO.

RAZOR-HONING DEVICE.

No. 918,909.

Specification of Letters Patent.

Patented April 20, 1909.

Application filed December 16, 1908. Serial No. 467,750.

To all whom it may concern:

Be it known that I, ALBERT D. RAY, citizen of the United States, residing at Cleveland, in the county of Cuyahoga and State of Ohio, have invented certain new and useful Improvements in Razor-Honing Devices, of which the following is a specification.

My invention relates to improvements in razor-honing devices, and, more particularly, 10 to means for carrying and supporting an ordinary hone-stone in proper position for honing a razor or other sharp edged tool.

The primary object of the invention is to provide an improved razor-honing device 15 which will enable any ordinary person to properly hone a razor or tool of similar character.

Another object of the invention is to provide an improved device of this class which 20 may be readily attached to or detached from hone-stones of varying length, and, when the hone-stone is mounted, will maintain the same at all times in a horizontal position, the hone-stone being also pivoted and mounted 25 in such a manner as to maintain the same in uniform contact with the edge of the razor irrespective of limited lateral or transverse oscillations of the razor blade usually incident to the manipulations of the same by inexperienced honers.

With the above mentioned objects in view, the invention consists in the novel construction, arrangement, and combination of parts, hereinafter described, illustrated in the 35 accompanying drawings, and particularly pointed out in the appended claims.

Referring to the drawings, forming a part of this specification, Figure 1, is a perspective view of a razor-honing device constructed 40 in accordance with one of the embodiments of my invention. Fig. 2, a side view, partly in side elevation and partly in longitudinal section. Fig. 3, an end view of one of the pivotally-mounted hone-clamping and carrying members. Fig. 4, a perspective view of a modified form of hone clamping and carrying member. Fig. 5, a perspective view of a modified form of pivot mounting 45 designed to coöperate with the form of hone-clamping and carrying member shown in Fig. 4.

Similar numerals of reference designate like parts throughout all the figures of the drawings.

55 The improved razor-honing device, in the present embodiment of my invention, com-

prises a base plate 1, provided at its ends with bearing standards 2. The bearing standards 2, are provided with base plates 3, each of said base plates, in the present instance, being slidably mounted in a longitudinal recess-way 4, of the base plate and adjustably secured therein by means of an adjusting screw 5. The adjusting screws 5 (one not shown), are threaded in the base plate 1, 60 and take through suitable openings in a clamping bar 6, adapted to be drawn down by the heads of the adjusting screws 5, to clamp the base plates 3, in a well known manner.

The hone-stone 7, may be supported and longitudinally-pivoted to the standards 2, in any suitable and convenient manner, said supporting and longitudinally-pivoting means, in the present instance, comprising a hone-bar 8, provided on its upper surface with a longitudinal recess-way 9. Hone-clamping and carrying members 10, are slidably and adjustably mounted in the hone-bar 8, by means of clamping screws 11, passing through the hone-bar 8, and through longitudinal 70 guide-slots 12, in base plates 13, of the clamping and carrying members 10, said base plates 13, being adapted to slide in the recess-way 9, and to be clamped in any position to which they may be adjusted by means of the clamping screws 11, threaded into a clamping-bar 14, whereby the turning of said screws 11, will 75 serve to draw the clamping-bar into clamping engagement with the base plates 13.

The hone-clamping and carrying members 10, in the present instance, are pivotally-mounted and secured to the bearing standards 2, by means of bearing-pins 15, said bearing-pins 15, being provided with milled heads 16, said bearing pins being secured by being threaded in the upper ends of the bearing standards 2, and provided with conical bearing ends 15^a, taking into bearing openings 17, of concavo-convex spring bearing 80 disks 18. The bearing disks 18, are mounted in pockets 19, on the face sides of the hone-carrying and clamping members 10. The arrangement just described permits of the adjustment of the bearing pins 15, against 85 the resistance of the spring bearing disks 18, whereby the tension of the pivot bearing may be readily regulated to regulate the lateral oscillation of the hone-stone.

It is obvious that the provision of the adjustable bearing standards 2, and hone-clamping and carrying members 10, adapts 90

the device to receive and contain hone-stones of varying lengths. The depending hone-bar 8, beneath the hone-stone 7, forms a depending counter balancing bar or weight 5 adapted to normally maintain the hone-stone 7, in a horizontal position. As a further means of maintaining the hone-stone in a substantially horizontal position as against any extended lateral oscillations in 10 incident to the honing of the razor blade, the base plates 13, of the hone-clamping and carrying members are provided with depending spring bars 20, the lower or free ends of which operate in bearing slots 21, at the ends 15 of the base plate 1. By this arrangement it is obvious that any extended lateral movement or inclination of the oscillating hone-stone 7, will operate against the resistance of the spring bars 20, and will be readily detected by the operator in the honing process.

In Figs. 4 and 5, I have shown a modified form of pivot mounting for the oscillating hone-stone 7. In this modified form the hone-clamping and carrying members 10, are 20 each provided with a trunnion 22, having its lower portion presenting a sharp angular edge 22^a, said trunnion 22, being adapted to be mounted in a substantially V-shaped bearing-recess 23, of a bearing-disk block 24, 25 movably mounted and adapted to turn in a bearing opening 25, of the bearing standards 2. In this form of mounting it is evident that as the upper or largest width of the trunnion 22, is less than the distance between the 30 upper edges of the V-shaped bearing recess 23, that slight oscillations of the hone-stone 7, may readily take place since the pivot will turn freely on the extreme angular edge 22^a, but any decided oscillation of the hone-stone 40 7, will cause one or the other of the sides of the trunnion to come into engagement with one or the other of the sides of the V-shaped bearing-recess 23, whereby the entire bearing-disk block will be turned in the bearing 45 opening 25, and the friction offered to the turning of this bearing disk will render a slight resistance to any decided or extended oscillation of the hone-stone 7, and will be readily detected by the operator. The bearing disk block 24, may be removably mounted in the bearing opening 25, in any suitable and convenient manner, preferably, by providing the periphery of the bearing block 25, with a circumferential groove (not shown) 50 55 adapted to receive the inner end of a small retaining screw 26, mounted at the top of the bearing standard 22.

Having thus described my invention, without having attempted to set forth all the forms in which it may be made, or all the modes of its use, I declare that what I claim and desire to secure by Letters Patent, is:—

1. A razor - honing device, comprising a base - plate, standards carried thereby and adjustably mounted therein, and a longitudinally pivoted counterbalanced hone-stone carried by and interposed between said standards. 65

2. A razor - honing device, comprising a base-plate, bearing standards carried at the ends thereof, a hone-stone interposed between and having its ends pivotally carried by said standards, and means for normally maintaining said hone-stone in a horizontal position. 70

3. A razor - honing device, comprising a base-plate provided at its ends with bearing-standards, a hone-bar, hone-clamping members adjustably secured to said hone-bar and pivotally-secured to said bearing standards, 80 and a hone-stone mounted above said hone-bar and having its ends clamped by said hone-clamping members. 75

4. A razor - honing device, comprising a base-plate, bearing standards slidably and 85 adjustably secured to the ends of said base-plate, a depending counter balancing hone-bar interposed between said standards, hone-clamping and carrying members slidably mounted and adjustably secured to the ends 90 of said hone-bar and longitudinally-pivoted to said standards, and a longitudinally-extending hone-stone having its ends engaged by said clamping members.

5. A razor - honing device, comprising a 95 base - plate provided with a recess - way, bearing-standards provided with base-plates slidably and adjustably mounted in said recess - way, hone - clamping and carrying members interposed between said bearing-standards, a hone-stone having its ends received and carried by said clamping and carrying members, means for longitudinally-pivoting said members to said bearing standards, and means for normally maintaining 100 said hone-stone in a substantially horizontal position. 105

In testimony whereof I have affixed my signature, in presence of two witnesses.

ALBERT D. RAY.
